DESIGN FOR A TOP FOR GOLF-STOCKINGS.

SPECIFICATION forming part of Design No. 27,440, dated July 27, 1897.

Application filed April 1, 1897. Serial No. 630,312. Term of patent 3½ years.

To all whom it may concern:

Be it known that I, TIMOTHY M. TWOMEY, a citizen of the United States, residing in the city, county, and State of New York, have invented and produced a new and original Design for an Ornamental Top for Golf-Stockings, of which the following is a specification.

In the drawings forming part of this specification, Figure 1 is a front elevation of the band, and Fig. 2 a central sectional elevation of the same.

My invention relates to golf-stockings, comprising the ornamental top therefor; and the design consists in the unitary article in its relation to shape or configuration, as shown in the accompanying drawings.

The top comprises two annular parts 1 2, one disposed within the other and joined to-

gether at the top 3 in a circular line, the part 2 being of slightly-smaller diameter to allow it to drop within the outer part 1 without wrinkling. The parts 1 2 are increased in thickness at the bottoms 4 5 by external ribbing 6 7, as shown. At or near the top of the inner portion 2 are longitudinal apertures 8. 25

Having described my invention, I claim—

The design for an ornamental top for golf-stockings, substantially as herein shown and described.

Signed in the city, county, and State of New York this 30th day of March, 1897.

TIMOTHY M. TWOMEY.
